INSTRUMENT CARRIER

Albert R. Casavant, Falling Water Road, Hixson, Tenn.

Filed Sept. 12, 1960, Ser. No. 62,100

Term of patent 14 years

(Cl. D3—4)

Fig. 3.

*Fig. 2.**Fig. 4.*Figure 1 is a front elevational view of an instrument carrier showing my new design;

Figure 2 is a side elevational view, thereof;

Figure 3 is a sectional view taken on the line 3—3 of Fig. 1; and

Figure 4 is a rear perspective view thereof showing the carrier in use, the dotted figure being for illustrative purposes only.

This is a continuation-in-part of my prior application, Serial No. D.54,770, filed February 27, 1959 which is now abandoned.

I claim:

The ornamental design for an instrument carrier, as shown and described.
